SHAFT BUSHING

Fred J. Steinke, South Bend, Ind., assignor to Reliance
Electric Company, Mishawaka, Ind.

Filed Dec. 14, 1970, Ser. No. 26,441

Term of patent 14 years

Int. Cl. D15—99

U.S. Cl. D46—1

Fig. 1

Fig. 2

Fig. 4

Fig. 3

Fig. 5

FIG. 1 is a perspective view of a shaft bushing embodying the present design;

FIG. 2 is an elevational view of one end of the bushing;

FIG. 3 is an elevational view of the end opposite that shown in FIG. 2;

FIG. 4 is a side elevational view; and

FIG. 5 is an elevational view of the side opposite that shown in FIG. 4.

I claim:

The ornamental design for a shaft bushing, substantially as shown.
